CLAIM

The ornamental design for an short wing sleeping mat for camping, as shown and described.

DESCRIPTION

FIG. 1 is a perspective view of the short wing sleeping mat for camping showing my new design.

FIG. 2 is a front view of the short wing sleeping mat for camping.

FIG. 3 is a rear view of the short wing sleeping mat for camping.

FIG. 4 is a left side view of the short wing sleeping mat for camping.

FIG. 5 is a right side view of the short wing sleeping mat for camping.

FIG. 6 is a top view of the short wing sleeping mat for camping; and,

FIG. 7 is a bottom view of the short wing sleeping mat for camping.

Any shading and cross-hatching are not features of the design but are utilized to illustrate the surface contours of the short wing sleeping mat for camping design in the drawings.
